UNITED STATES PATENT OFFICE

94,991

DESIGN FOR A CLOTH CUTTER

Nathan Ross, Los Angeles, Calif.

Application December 31, 1934, Serial No. 54,659

Term of patent 14 years

To all whom it may concern:

Be it known that I, Nathan Ross, a citizen of the United States, residing at Los Angeles, in the county of Los Angeles and State of California, have invented a new, original, and ornamental Design for Cloth Cutters, of which the following is a specification,

Reference being had to the accompanying drawing, forming part thereof.

Fig. 1 is a front perspective view of a cloth cutter showing my design.

Fig. 2 is a rear perspective view of Fig. 1.

I claim.

The ornamental design for a cloth cutter as shown.

In testimony whereof I affix my signature.

NATHAN ROSS.
